UNITED STATES PATENT OFFICE.

JOHN A. DOANE, OF HARTFORD, CONNECTICUT, ASSIGNOR TO PRATT & WHITNEY COMPANY, OF NEW YORK, N. Y., A CORPORATION OF NEW JERSEY.

DUPLEX VERTICAL SURFACE GRINDER.

Application filed May 31, 1923. Serial No. 642,613.

This invention relates to grinding machines and in particular to one adapted for rapid production of duplicate parts having flat ground surfaces.

More especially, the present invention relates to a form of surface grinding machine having two work supporting and rotating tables adapted to be successively indexed into and out of operative or grinding position relative to a grinding wheel.

A principal object of the invention is to provide indexing means for the rotating work tables enabling these tables to be indexed accurately and quickly into grinding or operative position.

Also it is an object of the invention to provide improved indicating or gaging means operating to indicate the progress of the grinding operation and also indicating when the grinding operation has been completed on the work pieces mounted on the table in operative position.

Another object of the invention is to provide a novel form of water guard completely surrounding the operative table to prevent water used in connection with the machine from being thrown out by the wheel. This guard comprises a number of plates adapted to move in a manner to permit indexing movements of the tables into and out of operative position.

A further object of the invention is to provide driving means for the work tables which will be operative while each of the tables is in position for grinding and inoperative while they are in their position for loading.

In addition, improved water controlling means are provided which permit water to be supplied to the work on the table in operative position and which will discontinue the supply during the indexing movements of the tables. For this purpose, a conduit is provided carrying the supply of water to the area within the periphery of the wheel, a valve in this conduit being opened and closed by means on the indexing member.

Also improved driving means for the grinding wheel are provided connecting the wheel spindle with a motor, preferably mounted within the base. The connection is such that it permits vertical adjustment of

the wheel spindle without effecting the driving connections and also permits proper operation when the motor and wheel spindles are slightly out of alignment.

Generally, the improvements incorporated in the grinding machine and forming the subject matter of this invention permit an operator to load work pieces upon one of the tables while the grinding operation is taking place on the other table.

When the grinding operation has been completed on work pieces on one table, indexing of the two tables takes place which may be manually controlled. By means of this indexing movement, the table which has been in operative position will be rotated to its inoperative or loading position and the table just loaded with work pieces will be rotated to its operative position. In this way, the machine permits practically continuous grinding operations upon blanks as the grinding is not interrupted during the time required to load and unload the work blanks on their respective tables.

With these and other objects in view, my invention consists in the features of construction and operation set forth in the following specification and illustrated in the accompanying drawings.

In the accompanying drawings annexed hereto and forming a part of this application, I have shown my invention embodied in a duplex vertical surface grinding machine but it is to be understood that many of the objects of the invention can be otherwise embodied and that the drawings are not to be construed as defining or limiting the scope of the invention, the claims appended to this specification being relied upon for that purpose.

In the drawings annexed hereto:

Fig. 1 is a side elevation of the complete machine, parts being broken away to more clearly show the construction of some of the parts.

Fig. 2 is a front elevation of the complete machine also having parts broken away to more clearly show their construction.

Fig. 3 is an elevation in section showing the driving means for the wheel and the mechanism for indexing and rotating the work tables.

Fig. 4 is a plan view of the complete machine, the parts being broken away to more clearly disclose the mechanism for indexing and rotating the work tables.

5 Fig. 5 is a plan view of the complete machine showing the arrangement of the guards surrounding the table, a side of the column being broken away to show the wheel feeding mechanism.

10 Fig. 6 is a vertical sectional view taken on the line 6—6 of Fig. 7 showing the indicating means forming a principal part of this invention.

15 Fig. 7 is a side elevation of the same parts. Fig. 8 is a sectional view taken on line 8—8 of Fig. 6.

Fig. 9 is a plan view of the indicating mechanism.

20 Fig. 10 is a vertical sectional view showing the controlling means for the water supplied to the wheel and work during the grinding operation.

Fig. 11 is a rear elevation of the wheel feeding means, and

25 Fig. 12 is a sectional view thereof taken on line 12—12 of Fig. 11.

In the above mentioned drawings, I have shown but one embodiment of the machine which is now deemed preferable but it is to be understood that changes and modifications may be made within the scope of the appended claims without departing from the spirit of the invention.

Briefly, my invention in its broadest aspect comprises the following principal parts: first, a base; second, a column on the base; third, a wheel head adjustably mounted on the column and having a rotatable abrasive wheel therein; fourth, driving means for the wheel preferably comprising a motor within the base and flexibly connected thereto to permit vertical adjustment of the wheel head; fifth, an indexing member rotatably mounted in the base; sixth, two rotatable tables on said member positioned preferably at diametrically oppositely disposed points; seventh, means to rotate the indexing member through a portion of a revolution; eighth, means to rotate the tables when they are in their operative position relative to the abrasive wheel; ninth, improved gaging means to indicate the progress of the grinding operation; tenth, water guards enclosing the table in operative position and permitting indexing movement thereof, and eleventh, controlling means for the supply of water to the wheel and work.

Referring more in particular to the figures of the drawings, a base 10 is provided having a column 11 mounted thereon for supporting the wheel head 12. As shown in Figs. 1 and 3, the column 11 is adjustably mounted on and secured to the base by means of special attaching means. Three sleeves 13 are threadedly mounted within the base

10 so that by rotating them their upper surfaces are vertically adjusted. The column 11 rests upon the upper surfaces of these sleeves 13, and, by means of suitable bolts 14 is retained in fixed position. Locking means 70 in the form of nuts 15 may also be provided for holding the sleeves 13 in adjusted position. As shown in Fig. 3, a washer 16, one surface of which is spherical, is interposed between the column 11 and sleeve 13 so that 75 adjustments of the column may be accommodated. The above described means enable the column to be readily adjusted so that the wheel head 12 will be disposed in position to move in a direction precisely normal to the surface of the work tables. For this purpose, suitable vertical ways are provided in the column 11. As these may be of any desired form, they do not require to be specifically shown or described.

80 The means for adjusting the wheel head 12 and for rotating the abrasive wheel 17 therein will presently be described. First, the mounting and indexing mechanism for the work tables will be described.

85 Within the base 10, a supporting member 20 for the tables is rotatably mounted in suitable bearings and is provided with an internal gear 21 mounted coaxially with its axis of rotation. This gear 21 may be driven 90 by a pinion 22 mounted on a vertical shaft 23 disposed within the base 10. Shaft 23 has splined thereto a clutch member 24 which may be moved into or out of engagement with clutch teeth on a sleeve 25 surrounding the shaft 23. For operating this clutch member 24 a pivoted hand lever 26 is provided, one end of the lever 26 engaging a circumferential groove 27 within the clutch member. The driving means for the sleeve 100 25, the shaft 23 and pinion 22, when the clutch 24 is in engaged position, comprise the following parts. A worm wheel 28 on a sleeve 29 provides driving means for a sleeve 30. Preferably worm wheel 28 is 110 driven by a worm 31 on a horizontal shaft 32 provided with a sprocket 33 adapted to be placed in connection with the armature shaft of a motor 34 by means of a suitable chain 35.

115 As it is essential that frictional driving means be used for driving the shaft 23, the sleeve 29 mounting the worm wheel 28 is therefore provided at its lower end with a flange 36 which is adapted to be engaged with another flange 37 fastened to the intermediate sleeve 30. The pressure between these two flanges 36 and 37 may be adjusted by means of the threaded nuts 38 engaging the intermediate sleeve. Rotation 120 therefore of the outer sleeve 29 frictionally rotates the inner sleeve 30 and, as clutch teeth are provided on sleeve 25 secured to the upper end of this latter sleeve, the driving shaft 23 will be rotated when the clutch 130

is in operative position. Through this frictional means, the motor 34 drives the worm wheel 28 and the outer sleeve 29 while the tables are being indexed into and out of their operative positions, and prevents breakage of the parts should anything interfere with the operation of the indexing movement.

In order to index this rotating or indexing member 20 through exactly one half a revolution and retain it in fixed position at the end of each indexing movement, a pin 40 is provided adapted to slide vertically and enter a depression 41 in the face of the internal gear 21 when moved to its upper position. This pin 40 may conveniently be mounted so that its lower end rests within a portion of the lever 26 for operating the clutch 24. Also the lever 26 is normally urged in a direction to disengage the clutch 24 and cause the pin 40 to enter the depression 41 within the internal gear 21 by a spring pressed plunger 42 engaging an arm 43 on the lever 26. It will be seen from this construction that upward movement of the lever 26 will cause the clutch 24 to engage the driving sleeve 25 to start the indexing movement of the rotatable member 20 and will simultaneously disengage the pin 40 from its recess. As soon as the member 20 starts to rotate the clutch 24 is held in engaged position by pin 40. As long as this pin 40 is prevented from entering one of its depressions 41, it cannot move upward and clutch 24 is retained in its lower position. With the parts in this position, the member 20 with the pin 40 urged against the lower face of the internal gear 21 is caused to slowly rotate. As soon as the member 20 has rotated so that the depression 41 in the internal gear 21 diametrically opposite the first depression is directly above the pin 40, the pin will move upward to engage it. Movement of the pin 40 will then permit oscillation of the hand lever 26 and will simultaneously disengage the clutch 24.

Mounted on this indexing member 20 are two work tables 45. Preferably these are of the rotatable type adapted to rotate about axes parallel to and at a distance from that about which the member 20 is rotated. These tables 45 may be driven by means of spur gears 46 formed integrally therewith. A central hub portion 47 of the tables 45 forms a journal fitting within a suitable bearing in the member 20. Also at the periphery of each of the tables 45 is a depending flange 48 in contact with an annular surface on the member 20 thus forming a thrust bearing. Fixed to and rotating with each of the tables 45 is a chuck 49 preferably of the magnetic type but obviously a chuck of any other type may be used. In engagement with the spur gears 46 on each of the tables 45 is a pinion 50 mounted on the upper end of a short shaft 51 rotatable with-

in the indexing member 20. On the lower end of these shafts 51 are spur gears 52 which may engage a pinion 53 on the upper end of another short shaft 54. Indexing movements of the member 20 cause the driving gears 52 for the tables 45 to be moved into and out of intermeshing position with their driving pinion 53.

From the above described construction, it will be seen that when the tables 45 are in their operative or grinding position the gear 50 on the driving shaft 51 for the table 45 will be rotated by the pinion 53, when it is indexed to its inoperative or loading position the gear 52 will be disengaged from the pinion 53 and the corresponding gear of the opposite table 45 will be brought into mesh therewith. In this way, the table 45 in operative position will be positively rotated while the table 45 in inoperative or loading position will be free to be rotated manually to facilitate the loading operation.

The magnetic chucks 49 on the tables 45 may be of conventional form and per se form no part of the present invention. A specific description thereof will therefore not be necessary. As these chucks 49 are rotated into and out of operative position, special means associated with the index member 20 are provided to magnetize and demagnetize them. On the lower face of the tables 45 are mounted contact rings 60 preferably embedded in a ring 61 of insulating material. These rings 60 are electrically connected respectively to the terminals of the coil windings of the chucks 49 in any desired manner. The contact rings 60 are engaged by spring pressed plungers 62 electrically connected with segments 63, the plungers 62 and segments 63 being mounted in the rotatable or indexing member 20. This construction permits the tables 45 to be rotated while the chucks 49 are continuously in contact with a source of electricity through plungers 62.

Fixed to a portion of the base 10 is a small bracket 65 on which are mounted two contact plugs 66 suitably insulated from each other. These plugs 66 are adapted to be connected to a suitable source of current in any conventional manner. Their upper ends resiliently press against the segments 63 on the rotatable member 20. Similar segments 63 and plungers 62 are mounted on diametrically opposite portions of the rotatable member 20 adjacent each of the tables 45. In either indexed position of the member 20 therefore one set of the segments 63 and plungers 62 is in contact with the source of current and the chuck 49 connected to the table 45 is therefore energized. Furthermore, as the plugs 66 are disposed directly below the operative table, the particular table 45 in operative position relative to the wheel 17 has its chuck 49 ener-

gized. As soon as one of the tables 45 and its chuck 49 is moved away from operative position, the segments 63 are disengaged from the plugs 66 and the chuck 49 becomes de-magnetized.

The driving shaft 54 for these tables 45 at its lower end is provided with a bevel gear 70 adapted to mesh with a bevel gear 71 on a horizontal shaft 72 having a plurality of gears 73 of different sizes slidably mounted thereon. Shaft 72 lies adjacent and parallel to a companion shaft 74 also having a plurality of gears 75 slidably mounted thereon. By means of rods 76 extending parallel to and below these two shafts 72 and 74, the gears 73 and 75 on the two shafts may be moved to different axial positions so that the driving shaft 54 for the tables 45 may be rotated at any one of a number of different speeds. As these shafts 72 and 74 and their gears 73 and 75 of different sizes form a change speed mechanism of a conventional sliding gear type, it is not thought necessary to describe it more particularly. To move the rods 76 controlling the positions of the slideable gears 73 and 75, a hand lever 77 is provided.

The driving shaft 74 of this change speed mechanism is preferably in driving relation with an intermediate shaft 78 through a pair of spur gears 79 which intermediate shaft is driven from the sprocket 33 on the driving shaft 32 by means of a second pair of gears 80. This construction permits the tables 45 to be rotated at any desired speed while in operative or grinding position, and to be free to be rotated manually when indexed to their inoperative or loading position.

Preferably a frictional connection between the driving shaft 32 and shaft 74 is provided so that the tables 45 may be started rotating gradually and without undue shock or jar. For this purpose a multiple disk type of clutch 82 is mounted on the driving shaft 32, the driven member of which carries one of the gears 80. To actuate this clutch, a spring 83 is provided normally forcing the disks of the clutch 82 into operative or driving relation. To release the clutch which is accomplished each time the member 20 is being indexed, a lever 84 is pivoted adjacent the clutch 82, an intermediate portion of which engages a part of the clutch 82 to disengage its disks. At the free end of the lever 84, a roller 85 is mounted which, during the indexing movement of member 20, rides on its outer periphery. With the lever in this outer position the clutch is disengaged. As the member 20 moves into each of its operative positions, the roller 85 enters a depression 86 formed in the periphery of member 20. This depression permits the lever 84 to oscillate slightly under the influence of the spring 83

and sufficient to cause engagement of the disks of clutch 82. As soon, therefore, as the member 20 has moved one of the tables 45 into operative position, the driving means become operative to rotate it. As soon, however, as the member 20 starts its indexing movement, the clutch 82 becomes disengaged which renders the driving means for the tables 45 inoperative.

From the above, it will be seen that when the grinding operation on work W mounted on one of the tables 45 has been completed and the other table 45 loaded, the operator has only to elevate the hand lever 26. Movement of this lever 26 serves to index the tables 45, start the one moved to operative position to rotate and simultaneously energize its magnetic chuck 49. Also during this index movement of the tables 45, the guards enclosing the operative table are deflected out of the path of movement of the member 20 and the tables 45 to permit this indexing movement.

During the grinding operation, the wheel 17 together with the wheel head 12 is moved downward, this being accomplished either automatically or manually. These means will now be described. A rotatably mounted screw 9 is provided suitably supported against axial movement within the column 11. This engages a nut 91 fixed into a projection 92 formed on the wheel head 12 so that rotation of the screw 90 raises or lowers the wheel head and its attached parts. To rotate the screw 90, a worm wheel 93 is fixed thereto engage by a worm 94. The worm 94 is keyed or otherwise fastened to a hollow shaft 95 suitably mounted horizontally within the column 11. Rotation of this worm 94 and its hollow shaft 95 therefore serves to feed the wheel head 12 upward or downward.

The means to rotate the shaft 95 and its worm by power means preferably step by step to slowly feed the wheel head 12 downwardly during operation will now be described. On one end of the shaft 72 for rotating the work tables 45 is a helical gear 100 in mesh with a helical gear 101 on a short shaft 102 mounted within the base. This shaft 102 carries an eccentric cam 103 which will be rotated while rotation of the tables 45 takes place. Contacting with the periphery of the cam 103 is a roller 104 on the end of a reciprocating rod 105, the opposite end of which is provided with rack teeth 106. A segmental gear 107 on a transverse shaft 108 in rear of the column 11 is oscillated by the reciprocatory movements of the rod 105 which oscillates a lever 109. A vertical rod 110 hinged to the transverse shaft 108 is therefore reciprocated vertically. The upper end of this latter rod 110 carries an oscillating member 111 having a pawl 112 engaging a ratchet

wheel 113 on the shaft 95 carrying the worm 94. This ratchet wheel 113 is therefore slowly rotated step by step which thus rotates the screw 90, the direction of rotation of which causes the wheel 17 to be fed downward. A hand wheel 114 fixed to the forward end of the hollow shaft 95 permits manual adjustment of the wheel head 12 in either direction when pawl 112 is disengaged so that the head 12 may be adjusted manually from the wheel 113.

By referring to Fig. 11, it will be seen that the oscillating member 111 carrying the feed pawl 112 is normally held by a spring 115 with one of its arms against an adjustable stop 116. Vertical movement of the rod 110 oscillates the member 111 away from the stop 116 to advance the ratchet wheel 113 and feed the wheel head 12. By varying the position of the stop 116 the oscillatory movements of the member 111 may be varied to increase or decrease the amount of feeding movement given the wheel head 12.

Associated with these wheel feeding means are additional means enabling the feeding movements of the wheel to be stopped at any predetermined point. For this purpose, the pawl 112 is held in operative engagement with the ratchet wheel 113 by magnetic means. An electro-magnet 120 when energized draws its armature 121 toward itself which movement oscillates a member 122 carrying the armature 121 and the pawl 112 against a spring 123 which permits the pawl 112 to ride upon the wheel 113. When the magnet 120 is deenergized by having its circuit broken, the spring 123 oscillates member 122 so that the pawl 112 cannot engage its ratchet wheel 113.

To interrupt the circuit for the magnet 120, a contact is made through the ratchet wheel 113. This wheel 113 has metal rings 125 on opposite sides suitably joined together electrically and properly insulated from the wheel. Contact plugs 126 and 127 resiliently engage these rings so that current can flow directly from one contact 126 through the rings 125 to the opposite contact 127. This circuit also includes a source of current, the electromagnet 120, and a manually operated switch.

Contact 127 constantly rides on one of the rings 125 but contact 126 may be forced away therefrom by an arm 130 mounted on and rotating with the ratchet wheel 113. It will be seen therefore that by setting the arm 130 relative to the wheel 113, the circuit may be interrupted and the pawl 112 thrown out of operative position at any point in the downward feeding movement of the wheel 17. This interruption of the feeding movement occurs when arm 130 lifts contact 126 from its ring 125.

To adjust the position of the arm 130 so

that it may be used to discontinue the feed at different points, the arm is carried on a part 131 in the form of a hub which may be forced against one side of the ratchet wheel 113 by a rod 132. This rod 132 extends entirely through the sleeve or hollow shaft 95 and at its forward end is fastened to a hub member 133. By means of a clamping lever 134, the relative rotative positions of the arm 130 and the sleeve 95 may be varied.

Thus by clamping the member 133 in predetermined relation relative to the sleeve 95, the feed may be continued any desired amount and then discontinued at predetermined points. By these means, the wheel 17 may be fed precisely to a predetermined position relative to the work table 45 at which point further feeding movement will be prevented.

As the pawl 112, while in its operative position, would prevent manual upward adjustment of the wheel 17, I provide a switch 136 in the circuit for the electro-magnet 120. By opening this switch 136, the pawl 112 is moved out of contact with the wheel 113 thus enabling the sleeve 95 and the parts carried thereby to be rotated freely in either direction to adjust the vertical position of the wheel 17.

One of the principal objects of the present invention is to improve the indicating means usable in connection with grinding machines permitting the progress of the grinding operation to be at all times evident to the operator. As the work tables 45 are indexed into and out of operative position, it is not practicable to have an indicator directly engage the work W on these tables. A separate member 140 mounted adjacent the operative table 45 and adapted to be engaged by the abrasive surface of the wheel 17 is therefore provided. An indicator 141, having a pointer 141^a, has an extension 142 which constantly bears against the upper horizontal surface of this member 140. This upper surface of the rotating member 140 is also adapted to be contacted by the abrasive surface of the wheel 17 simultaneously with its engagement with the work pieces W on one of the work tables 45. The upper surface of the rotating member 140 will therefore be abraded to a plane exactly contiguous with that of the upper surface of the work W. Also the abrasive action of the wheel 17 upon the work W on the work tables 45 may be observed by its corresponding abrasive action upon the surface of the rotating member 140. By means which will be described, the rotating member 140 is elevated slightly with each indexing movement of the tables 45. The wheel 17 therefore contacts with and abrades this member 140 exactly as if it were an extra piece of work on an independent table.

In order to rotate member 140, I provide

- driving connections from the driving shaft 72 for the indexing member 20 and work tables 45. This shaft 72 through helical gears 143 rotates an elongated shaft 144.
- 5 An extension 145 thereto having a bevel gear 146 at one end is in mesh with a bevel gear 147 on the lower end of a vertical sleeve 148. Within this sleeve 148 is a shaft 149 splined to the upper end of which is re-
- 10 movably mounted the rotatable member 140 contacted with by the wheel 17. This sleeve 148 and shaft 149 rotate within suitable bearings 150 and 151 fixed to one side of the column 11 preferably in a manner per-
- 15 mitting convenient vertical adjustment of the parts.
- On the indexing member 20 for the work tables 45 are diametrically opposite cam shaped projections 153 outstanding from its
- 20 periphery which are adapted to engage a spring actuated plunger 154. One of these projections 153 strikes the plunger 154 with each indexing movement of the tables 45.
- Movement of this plunger 154, through
- 25 means shown clearly in Fig. 8, rotates a ratchet wheel 155 splined to a vertically disposed shaft 156 parallel to and adjacent the shaft 149 and sleeve 148 for the rotating member 140. A gear 157 on this splined
- 30 shaft 156 engages another gear 158 on a sleeve 159 surrounding shaft 149. This sleeve 159 is threadedly engaged in its support 151 so that the effect of each movement of the plunger 154 is to rotate the
- 35 sleeve 159 and advance it axially a slight distance in accordance with the lead of its thread. It will be seen therefore that with each indexing movement of the tables 45, the rotating member 140 will be elevated.
- 40 This vertical movement will be very slight and in use one or two thousandths of an inch will be sufficient for its purposes. The vertical movement of the rotating member 140 also is timed to take place during the
- 45 indexing movement of the tables 45. At this time, the wheel head 12 and the wheel 17 are elevated above their operative or grinding position so that no abrasive action occurs upon member 140 at that time.
- 50 With work W to be ground mounted on the table 45 in operative position and with the rotating member 140 elevated the one or two thousandths, the wheel 17 is fed downwardly either manually or by power in
- 55 the manner above indicated so that its abrasive surface contacts with the work pieces W on the table 45. As soon as the wheel 17 has been fed downward to within one or two thousandths of its final position, its abrasive surface will contact with and abrade the rotating member 140. Thereafter, it will be seen that the surfaces of the work W and the upper horizontal surface of the rotating member 140 will be in exactly the same plane and will both be si-
- multaneously abraded. The indicator 141 with an extension of its movable member 142 in contact with the upper surface of the rotating member 140 enables the progress of the grinding operation to be at once evident by watching the pointer 141^a. Also completion of the grinding operation on the work W may be noted and further abrasive action discontinued.
- It is only when the work pieces W are practically finished that the abrasive wheel 17 comes into contact with the upper flat surface of the rotating member 140 and continued downward movement of the wheel simultaneously grinds the work pieces W and the member 140. This rotating member 140 is therefore worn away only the distance it is elevated with each indexing movement of the tables 45 namely one or two thousandths of an inch. As soon as the indicator 141, the pointer 141^a of which is in contact with the surface of this rotating member 140, comes back to a predetermined position on the dial, it is at once evident that the work pieces W have been brought to their final dimension.
- With each indexing movement of the tables 45 at which time the finished work W is indexed away from operative position and new unfinished work W is advanced for grinding, the rotating member 140 will be elevated slightly so that it will again be contacted by the wheel 17 operating on the next group of work pieces. The indicator 141 as shown is preferably of the dial type and is adapted to be adjusted relative to the rotating member in accordance with the thickness of the work W in any suitable manner. By these means, the indicator 141 continuously rests upon a member 140 which is rotatable at a slow speed and is adjustable vertically during normal operation through very small distances. The indicator 141 therefore does not ride upon the work W which frequently is in numerous pieces widely separated on the tables. In this way, the indicator 141 is not subjected to wide movements and its liability to injury or undue wear is materially reduced.
- Rotatably mounted about a vertical axis within the wheel head 12 is a spindle 160 carrying the wheel 17 preferably rotating upon two ball bearings. The lower one of these bearings 161 has its outer ring fixed within a recess formed within the head 12. The upper bearing 162 has its outer ring secured within a member 163 slidable vertically within the head 12. This member 163 is normally forced upward by springs 164, the effect of which is to resiliently hold the spindle 160 as high as permitted by the lower bearing 161. The inner rings of the lower and the upper bearings 161 and 162 are each secured directly to the spindle 160.
- The weight of the wheel head 12 and its

attached parts is counterbalanced by means of two weights 170, one on each side of the machine. These weights 170 are attached to opposite sides of the head 12 by cables 171 passing over suitable idlers 172. Preferably the combined weight of the counterweights 170 exceeds that of the head 12 and its attached parts so that the head 12 is held as high as permitted by the threads 10 on adjusting screw 90. At the lower end of the spindle 160, the wheel 17, preferably of annular form, is attached in any preferred way.

In order to rotate the spindle and its abrasive wheel at high speed and in a manner which will permit free axial movement thereof over a wide range of adjustment, the following mechanism is provided: Within the base 10 and directly below the column 11 as shown in Fig. 3 is an electric motor 180, the armature shaft 181 of which extends vertically. Also, as shown in this figure, the shaft 181 has a sleeve 182 attached to its upper end. The sleeve 182 is attached to the armature shaft 181 by means of a flexible coupling formed by an annular thin metal disk 183. The outer periphery of this disk 183 is attached to a flange 184 on the lower end of the sleeve 182 and its inner periphery is attached to a member 185 and directly keyed to the armature shaft 181. This form of coupling permits limited axial and angular adjustment by flexure of the disk 183.

35. This sleeve 182, as shown, is in alignment with a corresponding sleeve 187 fixed to and moving with the wheel spindle 160. As the upper sleeve 187 is in every way similar to the lower one 183 and is flexibly attached to the spindle 160 in the same manner as sleeve 183, it will not require description. Each of these sleeves 183 and 187 is provided with an axial opening splined throughout its length.

45. Between the sleeves 182 and 187 is provided a connecting shaft 190 having longitudinally extending projections thereon engaging in correspondingly disposed grooves or splined portions in the sleeves. 50. By means of these projections and grooves respectively provided on the shaft and sleeves, driving connections are provided between the motor 180 and the wheel spindle 160 permitting extensive adjustment. Also, 55. as the sleeves 182 and 187 are connected respectively to the motor 180 and spindle 160 respectively by means of flexible couplings the motor and wheel spindle do not have to be accurately aligned. In this manner, also, the wheel spindle 160 and wheel 17 may be vertically adjusted to any desired position during its rotation with a minimum of resistance. To assemble or dis-

60. assemble these parts or to remove and replace a wheel 17, it is only necessary to

insert or remove the shaft 190 vertically through an opening within the spindle 160.

It is essential that the table in operative or grinding position be suitably enclosed by guards forming suitable enclosing plates 70 so that water or other fluid used in connection with the machine may not be driven outwardly during the grinding action. Also these guards or plates must be so disposed and movably mounted that they will permit 75 indexing movements of the member 20 and tables 45. For this purpose, I form these water guards or plates so that they are adapted to move to and from their operative 80 positions shown most clearly in Fig. 5.

These guards consist first of a plate 200 mounted in a fixed vertical position directly on the indexing member 20 so that it moves therewith. In the operative positions of the tables 45, this plate 200 stands transversely of the machine and midway between the two tables 45. Its operative position is shown in full lines in Fig. 5. On either side of this guard 200 on the indexing member 20, are side plates 201 and 202 hinged to portions on opposite sides of the column 11. The guard plate 201 on the right is curved at its forward end and joins one end of the transverse or central guard plate 200. When the tables 45 are being indexed, the 90 surface of one of them contacts with the guard 201 which causes it to be deflected to its extreme outer position shown in dotted lines.

The guard plate 202 at the left hand of the tables 45 is also hinged to the column 11 and is provided with a cam-shaped projection 203 at its free or outer end. This projection 203 is engaged by the periphery of the tables 45 during the indexing movement and causes this guard plate 202 to be moved outward to the extreme position shown in dotted lines. When the tables 45 have completed their indexing movement, the two hinged guard plates 201 and 202 110 spring back into close contact with opposite ends of the plate 200 mounted on the indexing member 20. With the guard plates in this position the operative table 45 is 115 completely enclosed thus preventing water from being thrown out from the machine.

The means for constantly flooding the wheel 17 and work W with water or other fluid comprises a conduit 210 extending from a pump 211 in the base 10 of the machine. 120 This conduit 210 may extend to a semi-circular ring 212 directly below the wheel 17 to the opposite ends of which flexible tubes 213 may be fitted. These tubes 213 have nozzles 214 at their ends which may be adjustably positioned and held relative to the wheel 17 and work W to properly 125 guide the flow of water.

As the grinding operation is discontinued while the tables 45 are being indexed, it 130

is desirable to interrupt the flow of water to the wheel 17 and work W during this period. I therefore provide a valve casing 215 in the water supply conduit 210 normally having its valve 216 forced toward its closed position by a suitable spring 217. This spring 217 may preferably be mounted within an extension to the casing 215 to surround the valve stem 218. The valve stem 218 is extended from this valve casing 215 to a point where its upper end may contact with a cam 219 fitted to and depending from the indexing member 20. This cam 219 is so located on the member 20 that it is directly over the valve stem 218 when the member 20 is in one of its indexed positions. Two of these cams 219 oppositely disposed on the member 20 are provided, one disposed thereon for each of the indexed positions of the member 20. The valve stem 218, when it strikes one of these cams 219, will be forced downward thus opening the valve 216 and permitting water to flow to the wheel 17 and work W. Also the valve 216 will be open at all times during which the grinding operation is taking place. As soon, however, as the member 20 starts its movement to index the tables 45, the cam 219 is rotated away from the valve stem 218 and the valve 216 is closed by the action of the spring 217. In this way the valve 216 is closed during the entire period of the indexing movement but, as soon as the member 20 approaches each of its indexed positions, the valve stem 218 strikes one of the cams 219 thus again opening the valve 216 and permitting the water to flow.

Special means are incorporated in the base 10 of the machine to direct the passage of the water from the tables 45 to a reservoir provided either in the base 10 or conveniently located adjacent thereto. From the tables 45 the water drops to portions of the base 10 indicated at 222. Spaced through this portion of the base 10 are baffles 223 forming pockets between them which retain a part of the water. It is not until water overflows the baffles 223 that it can pass through the opening 224.

By means of this construction, the major portion of the water must pass through more than one pocket between the baffles 223 before it passes to the opening 224. While passing these baffles, it may deposit a large amount of the sediment which may be readily removed from the pockets 222.

The motor 24 for rotating and indexing the tables 45 and mounted within the base 10 of the machine may be of any type dependent upon the source of current available. As it is necessary to have direct current for operating the magnetic chucks 49, I provide a special generator 230 for this purpose. As shown in Fig. 2, this generator 230 may

be mounted within the base 10 being attached to the lower surface of a horizontal part of the base in the same manner as the motor 24. Preferably the armature shafts of the motor 24 and the generator 230 are approximately in alignment and are connected together by means of a shaft 231 and a flexible joint 232.

What I claim is:

1. A surface grinding machine comprising, in combination, a base, a rotatable wheel mounted thereon upon a vertical axis, two work supporting and rotating tables, a rotatable supporting member mounted within the base and carrying the tables at a distance from their axes of rotation, means to actuate said member to alternately move said tables into and out of operative position relative to the wheel, and means to rotate said tables while in their operative position, said means becoming automatically disengaged when said tables are in their inoperative or loading position. 75

2. A surface grinding machine comprising, in combination, a base, a rotatable wheel mounted thereon upon a vertical axis, two work supporting and rotating tables, a rotatable supporting member mounted within the base and carrying the tables at a distance from their axes of rotation, power means to index said supporting member to alternately move said tables into and out of operative position relative to the wheel, and frictionally driven means to index said member and to rotate said tables. 90

3. A surface grinding machine comprising, in combination, a base, an abrasive wheel rotatably mounted adjacent thereto, means to adjust the position of said wheel, a member rotatably mounted on said base, means 105 to index said member one half of one revolution, two tables mounted on diametrically opposite parts of said member, whereby indexing movements of said member will alternately and successively move said tables into and out of operative position, frictionally driven means to index said supporting member, and means to rotate said tables at any one of a plurality of different speeds. 110

4. A surface grinding machine comprising, in combination, a base, a rotatable wheel mounted thereon, a plurality of rotatable work supporting tables, means to move said tables alternately into and out of operative position relative to the wheel, and a gaging device comprising a rotatable member mounted adjacent the operative position of the tables and adapted to be continuously contacted by the wheel, and an indicator engaged by said member whereby the progress 120 of the grinding operation can be observed. 115

5. A surface grinding machine comprising, in combination, a base, a rotatable wheel mounted thereon, a plurality of rotatable work supporting tables, means to move said 125

tables alternately into and out of operative position relative to the wheel, and a gaging device comprising a rotatable member adjacent the operative position of the tables and adapted to be continuously contacted by the wheel, means to adjust the position of the rotatable member, and an indicator engaged by said rotatable member whereby the progress of the grinding operation can be observed.

6. A surface grinding machine comprising in combination, a base, a rotatable wheel mounted thereon, a plurality of rotatable work supporting tables, means to advance said tables alternately into and out of operative position relative to the wheel, and a gaging device comprising a rotatable member adjacent the operative position of the tables and adapted to be continuously contacted by the wheel, means to adjust the position of the rotatable member, said means being actuated with each of said table advancing movements, and an indicator engaged by said rotatable member whereby the progress of the grinding operation can be observed.

7. A surface grinding machine comprising in combination, a base, a work supporting table on said base, a wheel head, a rotatable wheel in said wheel head, means comprising a ratchet wheel and pawl to adjust the position of said wheel relative to the table, magnetic means controlling the operative or inoperative position of the pawl to render the wheel adjusting means operative, and means rotating with the ratchet wheel to discontinue the adjustment of the wheel at any predetermined point in its downward movement.

8. A surface grinding machine comprising in combination, a base, a work supporting table on said base, a wheel head, a rotatable wheel in said wheel head, means comprising a ratchet wheel and pawl to adjust the position of said wheel relative to the table, magnetic means controlling the operative or inoperative position of the pawl to render the wheel adjusting means operative, and means to discontinue the adjustment of the wheel at any predetermined point in its downward movement, the position of said last named means being adjustable on the ratchet wheel.

9. A surface grinding machine comprising in combination, a base, a work supporting table thereon, a wheel head having a wheel spindle and wheel rotatably mounted therein and movable toward and from said table, means to rotate said wheel comprising a motor, and flexible connections between said motor and wheel spindle, said connections having an intermediate removable splined shaft.

10. A surface grinding machine comprising in combination, a base, a work sup-

porting table thereon, a wheel head having a wheel spindle and wheel rotatably mounted therein and movable toward and from said table, means to rotate said wheel comprising a motor, splined sleeves respectively connected flexibly to said motor and wheel spindle, said sleeves being in driving connection with each other by means of an intermediate removable splined shaft.

11. A surface grinding machine comprising in combination, a base, a work supporting table thereon, a wheel head having a wheel spindle and wheel rotatably mounted therein and movable toward and from said table, means to rotate said wheel comprising a motor, splined sleeves respectively connected by means of thin flexible disks to said motor and wheel spindle, said sleeves being in driving connection with each other by means of an intermediate removable splined shaft.

12. A surface grinding machine comprising in combination, a base, a work supporting table thereon, a wheel head having a wheel spindle and wheel rotatably mounted therein and movable toward and from said table, means to rotate said wheel comprising a motor mounted within the base upon an axis and in alignment with the wheel spindle, and flexible connections between said motor and wheel spindle, said connections forming driving connections between said motor and wheel spindle permitting axial adjustment.

13. A surface grinding machine comprising in combination, a base, a work supporting table thereon, a wheel head having a wheel spindle and wheel rotatably mounted therein and movable toward and from said table, means to rotate said wheel comprising a motor mounted within the base upon an axis in alignment with the wheel spindle, and flexible connections comprising disks attached respectively to the said motor and wheel spindle, said connections forming driving connections between said motor and wheel spindle permitting axial adjustment.

14. A surface grinding machine comprising in combination, a base, two work supporting tables thereon, a wheel head having a wheel rotatably mounted therein and movable toward and from said table, means to index said tables alternately into operative position, water supplying means adapted to direct water upon the wheel and work during the grinding operation, and means to discontinue said supply of water during the indexing movement.

15. A surface grinding machine comprising in combination, a base, two work supporting tables thereon, a wheel head having a wheel rotatably mounted therein and movable toward and from said table, a rotatably supporting member adapted to index

said tables alternately into operative position, water supplying means adapted to direct water upon the wheel and work during the grinding operation, and means on said rotatable supporting member to control said supply of water during the grinding operation and permit said supply to be discontinued during the indexing movement.

16. A surface grinding machine comprising in combination, a base, two work supporting tables thereon, a wheel head having a wheel rotatably mounted therein and movable toward and from said table, a rotatable supporting member adapted to index said tables alternately into operative position, water supplying means adapted to direct water upon the wheel and work during the grinding operation, a valve in said water supplying means to hold said valve open during the grinding operation, and means permitting said valve to close during the indexing movement.

17. A surface grinding machine comprising in combination, a base, two work supporting tables thereon, a wheel head having a wheel rotatably mounted therein and movable toward and from said table, a rotatable supporting member adapted to index said tables alternately into operative position, water supplying means adapted to direct water upon the wheel and work during the grinding operation, cam means carried by said supporting member to normally maintain said supply open, and means to discontinue said supply during the indexing movement.

18. A surface grinding machine comprising in combination, a base, two work supporting tables thereon, a wheel head having a wheel rotatably mounted therein, and means to index said tables alternately into operative position, guard plates enclosing the operative table during the grinding operation, said guards being movable to permit indexing movement of the tables.

19. A surface grinding machine comprising in combination, a base, two work supporting tables thereon, a wheel head having a wheel rotatably mounted therein, and means to index said tables alternately into operative position, guard plates enclosing the operative table during the grinding operation, one of said guards being carried by and movable with the indexing means, the other guards being movable laterally to permit indexing movement of the tables.

20. A surface grinding machine comprising in combination, a base, two work supporting tables thereon, a wheel head having a wheel rotatably mounted therein, and means comprising a rotatable supporting member to index said tables alternately into operative position, a guard plate thereon partly enclosing the operative table during the grinding operation, and oppositely disposed guards movably mounted on the machine to permit indexing movement of the tables.

In testimony whereof, I hereto affix my signature.

JOHN A. DOANE.
